UNITED STATES PATENT OFFICE.

MORRIS PEAK, OF KANSAS CITY, MISSOURI.

PUZZLE.

1,367,561.

Specification of Letters Patent.

Patented Feb. 8, 1921.

Application filed July 19, 1920. Serial No. 397,180.

To all whom it may concern:

Be it known that I, MORRIS PEAK, a citizen of the United States, and a resident of Kansas City, in the county of Jackson and State of Missouri, have invented certain new and useful Improvements in Puzzles, of which the following is a specification.

My invention relates to puzzles of that particular class in which a board is provided having pens or inclosures formed thereon provided with gates or openings so arranged as to render it extremely difficult to cause spheres which are movable over the board to enter a particular pen.

It is a purpose of my invention to provide a puzzle of this character in which a pair of pens or inclosures are provided made up of a plurality of arcuate flanges arranged to provide a plurality of circular channels communicating with each other at different points so as to render it extremely difficult to manipulate the board so as to direct the spheres from the pens into a central pen or goal interposed between the two pens.

I will describe one form of puzzle embodying my invention and will then point out the novel features thereof in claim.

In the accompanying drawings:

Figure 1 is a view showing in top plan one form of puzzle embodying my invention.

Fig. 2 is a central longitudinal sectional view of the puzzle shown in Fig. 1.

Referring specifically to the drawings, in which similar reference characters refer to similar parts, B designates a board having rounded ends and upon which is formed upstanding flanges arranged to provide an intermediate inclosure or pen P and two end pens P¹ and P². The edge of the board B is provided with an unbroken upstanding flange 15, which forms the perimeter of the end pens P¹ and P² and the end inclosing portions of the pen P. The intermediate pen P is separated in part from the end pens P¹ and P² by flanges 16 and 16^a disrupted at corresponding points intermediate their ends to provide gates 17 and 17^a through which communication is effected between the end pens and the center pen. The end pens P¹ and P² are made up of a plurality of circular flanges arranged concentrically of each other and spaced apart to provide circular channels. The innermost flange is designated at 18 and is disrupted to provide a gate 18^a for effecting communication between the space within the

flange and the channel between the innermost flange and the adjacent flange 19. The flange 19 is also provided with a gate 19^a which effects communication between the channel between the flanges 18 and 19 and the channel between the flanges 19 and 20. The flange 20 of the pen P² is arranged in spaced relation to the flange 15 and the flange 16 to provide a circular channel 65 which communicates with the channel between the flanges 19 and 20 by a gate 20^a, and with the pen P through the gate 17. Similarly, the flange 20 of the pen P¹ is arranged in spaced relation to the flange 70 15 and the flange 16^a so as to provide a circular channel which communicates with the channel between the flanges 19 and 20 by the gate 20^a and with the opening P through the gate 17^a.

As shown in Fig. 1, the several gates of the pens P¹ and P² are arranged at points diametrically opposite to each other so as to render it extremely difficult for the passage of a sphere from one channel to the other. 80 It will be further noted that the gates of the pen P¹ are disposed at right angles to the gates of the pen P², this arrangement rendering it yet more difficult to direct the spheres from channel to channel.

The spheres used in the puzzle are designated at S and are preferably in the form of marbles of a diameter to freely roll between the flanges and through the several gates.

In operation, the spheres are first assembled within the space defined by the flanges 18 of the pens P¹ and P², the object of the puzzle being to roll the several spheres from the center of the pens P¹ and P² into 95 the central pen P. This is accomplished by so manipulating the board that the spheres will roll outwardly from the center of the pens through the several gates and channels until they finally reach the central pen P 100 through the gates 17 and 17^a. Because of the staggered arrangement of the gates between the several channels and between the end pens and the central pen, it will be clear that great skill is required in manipulating 105 the board to direct the spheres from the end pens to the center pen.

Although I have herein shown and described only one form of puzzle embodying my invention, it is to be understood that various changes and modifications may be made herein without departing from the

spirit of the invention and the spirit and scope of the appended claim.

What I claim is:

5 A puzzle comprising, a board having rounded ends, a continuous upstanding flange formed on the edge of the board, reversely curved flanges connecting the edge flange at different points to provide a central inclosure and end inclosures, two sep-
10 arate and distinct sets of circular flanges

formed on the board within said end inclosures, each set of circular flanges being arranged concentrically of each other to provide intervening channels therebetween, said reversely curved flanges and said circular 15 flanges being formed with gates or openings to effect communication between the several channels and between the end inclosures and the central inclosure.

MORRIS PEAK.
